A. BARTHOLDI

GARMENT HANGER

Filed Sept. 28, 1922

Fig. 1

Fig. 2

Inventor
Amlo Bartholdi.
By his Attorney
Thoula D. O'Farril.

UNITED STATES PATENT OFFICE.

AMLO BARTHOLDI, OF JERSEY CITY, NEW JERSEY.

GARMENT HANGER.

Application filed September 28, 1922. Serial No. 591,021.

To all whom it may concern:

Be it known that I, AMLO BARTHOLDI, a subject of King of Italy, residing at Jersey City, in the county of Hudson and State of New Jersey, have invented certain new and useful Improvements in Garment Hangers, of which the following is a specification, reference being had therein to the accompanying drawing.

10 My invention relates to improvements in clothes hangers, which may be constructed from one piece of cardboard, and one of the objects of my invention is to provide a practical clothes hanger which can be constructed cheaply and quickly.

15 I attain these objects by a device such as is illustrated in the accompanying drawings, in which Fig. 1 is a perspective view, and Fig. 2 is a similar view of a modification thereof.

20 The card is bent at the center forming the channel 3, and continues upward forming shoulders 5 and 6, and a neck portion 7, 8, in which holes 9 and 10 are provided 25 for hanging.

The neck portion of the device shown in Fig. 1 is provided in one side with a slit 11 and the other side is provided with a tongue 7 adapted to pass through the slit as shown, both of the neck portions having the holes 9 and 10 so arranged as to be in alignment when the neck portions are interlocked, thus serving as a convenient means for suspending the hanger. In the modification shown in Fig. 2, the neck portions are slit half way transversely in opposite directions, that is to say, the neck 8 of the shoulder portion 5 is slit from left to right half way as indicated at 8', and the neck 7 40 of the shoulder portion 6 is slit half way

from right to left as indicated at 7', so that when the slits are engaged, the holes 9, 10 come into alignment. In both forms of hanger shown in Figs. 1 and 2, the sides are cut away as indicated at 12 to provide 45 clearance for the passage of the trouser legs and serve as a trouser support, but in the modification shown in Fig. 2, the cut away portions such as 13, 14, instead of being completely cut away, are only cut 50 at the three sides allowing the flaps 13, 14 to remain as a reinforcement or strengthener, and these if desired may be glued fast to the sides 5, 6.

Of course it will be understood that various modifications may be made in the construction and arrangement of parts without departing from the spirit of the invention as claimed.

I claim:

1. A clothes hanger formed from an integral sheet of material folded back upon itself, thereby providing a neck portion and supporting means forming a double thickness of material, one of which passes 65 through the other, thereby providing an interlock.

2. A clothes hanger formed from an integral sheet of material folded back upon itself, thereby providing a neck portion and supporting means forming a double thickness of material, one of which passes through the other, thereby providing an interlock, and in combination therewith a transverse slot through said portions providing a trouser hanger.

In testimony whereof I hereunto affix my signature.

AMLO BARTHOLDI.
